ELECTRICAL WEFT DETECTOR

Filed Aug. 2, 1929

UNITED STATES PATENT OFFICE

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

ELECTRICAL WEFT DETECTOR

Application filed August 2, 1929. Serial No. 383,033.

This invention relates to improvements in electrical weft detectors for looms and it is the general object of the invention to provide a detector of this type wherein mechanical adjustments of the mechanism may be made without disturbing the electrical connections.

A form of electrical weft detector which has heretofore been proposed includes a pair of insulated contact elements to enter a shuttle and be electrically connected upon a depletion of weft. In order to accommodate the differing diameters of the weft these electrodes have been independently and resiliently mounted and it is an important object of my present invention to employ the springs which act to hold the detecting elements in normal position to convey current to or from the elements.

In the operation of the ordinary loom it is desirable that the detector be movable within a limited range of adjustments with respect to the weft supply and it is a further object of my present invention to provide for this adjustment while employing an electro-magnetic member which is movable with the detector so that the connections therefor are not disturbed during the adjustment. In this connection it is a further object of my present invention to provide for a limited adjustment of the electro-magnetic member with respect to the carrier for the electrodes on which it is mounted.

With these and other objects in view which will appear as the description proceeds, my invention resides in the combination and arrangement of parts hereinafter described and set forth in the claim.

In the accompanying drawings, wherein a convenient embodiment of my invention is set forth,

Fig. 1 is a top plan view of an electric weft detector made according to my present invention, certain parts being shown in section,

Fig. 2 is a side elevation of my detector, the shuttle being shown in section,

Figs. 3, 4, 5 and 6 are detailed vertical sections on an enlarged scale on lines 3—3, 4—4, 5—5, and 6—6, respectively, of Fig. 1,

Fig. 7 is an enlarged vertical section

through the electromagnetic element, in this instance a solenoid, and

Fig. 8 is a diagrammatic plan view of one of the electrodes.

The invention has been illustrated in connection with a form of mechanism particularly adaptable to a multicolor weft replenishing loom, although I do not wish to be limited to this type of loom.

Referring to Figs. 1 and 2, I have shown a bracket 10 which has secured thereto the foot 11 of a stand or platform 12. The latter is provided with a slot 13 which extends substantially parallel to the shuttle S.

Formed either as part of the bracket 10 or supported independently thereof is an arm 14 having a vertical slot 15 through which extends an actuator lever 16. This lever has a downward movement on detecting beats of the loom and when uninterrupted effects no change in the operation of the loom. When weft is depleted, however, a controller 17 will move under said lever, to interrupt its downward movement, thereby calling into action mechanism to effect a change in the operation of the loom, such, for instance, as automatic weft replenishment or loom stoppage for hand replenishment. The controller 17 is pivoted to a stud 18 mounted on the arm 14 and is provided with a laterally extending forked arm 19 by means of which the controller may be moved.

The matter thus far described forms no part of my present invention, the actuator lever 16 being substantially the same in operation and structure as that shown in prior patent to Ryon No. 1,030,748 and the controller 17 being of a form now in general use on certain types of side slipping weft detectors.

In carrying my invention into effect I provide a carrier 30 which is preferably made of insulating material and comprises upper and lower plates 31 and 32, respectively, which are separated by front and back bearing members 33 and 34, respectively. Screws 35 may be used to secure the plates and bearing members together as a unit. The plates are also separated by a brace block 36 which has a slot 37 to align with slots 38 and 39 formed in

the plates 31 and 32, respectively. A bolt 40 extends through the aligning slots of the carrier and also through the slot 13 and serves to hold said carrier in fixed position on the platform or stand 12.

5 A pair of oppositely charged detector rods or members 41 and 42, respectively, are slidably mounted through the front and rear bearing blocks 33 and 34 but are out of electrical contact with each other due to the fact that said bearing blocks are formed of insulating material. Each of the detector rods or members is surrounded by a compression spring 43 having relatively large forward 10 coils 44 and comparatively small rear coils 45. Coils 45 are normally of such size as to grip the rods tightly enough to resist relative movement with respect to them. The forward end of the coil spring around the member 42 extends to a binding post 46 which is mounted on the upper plate 31, being shown herein as extending through a hole 47 in the forward bearing plate 33. The coil spring surrounding the other contact member 41 is connected to a binding post 48. It is to be understood that the springs are of sufficient resilience to hold the detector members rearwardly in normal position while at the same time conducting current sufficiently 20 well to operate satisfactorily in an electric circuit.

35 The electro-magnetic element comprises a solenoid 50 which is wound preferably on a thin non-magnetic tube 51 supported at the upper end thereof by a transverse plate 52 extending over the upper carrier plate 31 and held thereto by means of bolts 53. The latter extend through slots 54 which extend in a direction substantially perpendicular to the 40 axes of the detector rods 41 and 42. A small collar 55 may be soldered or in any other way secured to the tube 51 so as to support the solenoid 50 with respect to the plate 52.

45 The core 56 of the solenoid is freely movable in the tube 51 and extends downwardly, having threaded thereon upper and lower nuts 57 and 58, respectively, between which lies the forked end 19 of the controller 17. An abutment 59 on the controller element engages a similar abutment 60 on the arm 14 to position the arm 19 and therefore the solenoid.

55 A wire 61 connects the binding post 48 with one side of the solenoid, while another wire 62 connects the other side of the solenoid to a third binding post 63. A source of electrical current, such as a battery P, has one side thereof connected by means of wires 64 to the binding post 46 and has the other side connected by means of another wire 65 to the binding post 63.

65 Under normal conditions the controller is in the position shown in Fig. 6, lying to one side of the actuator lever 16 so as not to interrupt the downward movement thereof.

When sufficient weft is present the advancing shuttle will move both the detector rods 41 and 42 forwardly against the action of the springs 43, and the yarn, being of an insulating material, will prevent electrical contact 70 between the rods. When insufficient weft remains on the bobbin, however, a metallic ferrule or other conducting surface designated at 70 in dotted lines in Fig. 1 will electrically connect the rods 41 and 42, whereupon current will flow through the following circuit: battery P, wire 64, binding post 46, spring 43 on rod 42, rod 42, ferrule 70, rod 41, the spring on the latter to binding post 48, wire 61 through the solenoid 50, wire 62 to binding post 63 and wire 65 back to the battery. Current flowing in this circuit will energize the solenoid and cause the latter to lift its core 56, thereupon requiring the lower nut 58 to rock the control member 17 until the same 80 assumes the dotted line position shown in Fig. 6 to interrupt downward movement of the actuator lever.

In order to withdraw the feeler at the time of transfer to make room for the incoming bobbin I secure a finger 71 to the rods and project the same upwardly to extend into the path of a stud 72 movable with the transfer mechanism not shown. The finger is preferably formed of insulating material so as to 90 prevent electrical contact between rods at the time of withdrawal, otherwise the indication would be repeated.

If it be desired to move the feeler with respect to the bracket 10 and the adjustment 100 is sufficient to interfere with the correct operation of the solenoid with respect to the controller, the bolts 53 may be loosened and the plate 52 given an adjustment relatively 105 to the carrier in the proper direction.

From the foregoing it will be seen that I have provided an electrical weft detecting unit carrying the detectors and the solenoid or other form of electro-magnetic member in normally fixed relation, that is, the detectors and the solenoid are supported by the carrier and movable as a whole with the latter. Furthermore, it will be seen that the binding posts 46 and 63 may be connected to the battery and all other connections between the detector and solenoid move with the carrier. Also, the solenoid is susceptible of a slight adjustment relatively to the carrier. Furthermore, the springs which hold the detector rods in rearward position are the means by which current passes from said rods to the circuit which includes them. Again, it will be seen that the means for withdrawing the detectors at the time of transfer prevents the electrical contact of the rods 41 and 42 and thereby effectively avoids a repetition of the indication.

Having thus described my invention it will be seen that changes and modifications may be made therein by those skilled in the 130

art without departing from the spirit and scope of the invention and I do not wish to be limited to the details herein disclosed, but what I claim is:

- 5 In an electrical weft detector for looms, a detector rod of electric current carrying material, a carrier for the rod, a coiled compression spring surrounding the rod and having certain coils thereof in tight engagement
- 10 with the rod and having other larger coils through which the rod is free to move, the larger coils bearing against the carrier to hold the detector yieldingly in normal position, and an electric circuit electrically connected to the coiled spring.
- 15

In testimony whereof I have hereunto affixed my signature.

ELBRIDGE R. HOLMES.
